US0D1058522S

(12) **United States Design Patent** (10) **Patent No.:** **US D1,058,522 S**
(45) **Date of Patent:** **** Jan. 21, 2025**

(54) **CONTROL UNIT**

(71) Applicant: **Furuno Electric Co., Ltd.**, Hyogo (JP)

(72) Inventors: **Daigo Dohi**, Takarazuka (JP); **Takashi Ohmori**, Nishinomiya (JP)

(73) Assignee: **Furuno Electric Co., Ltd.**,
Nishinomiya (JP)

(**) Term: **15 Years**

(21) Appl. No.: **29/913,557**

(22) Filed: **Oct. 4, 2023**

(51) LOC (15) Cl. **13-03**

(52) U.S. Cl.

(57) **CLAIM**

The ornamental design for a control unit as shown and
described.

DESCRIPTION

FIG. 1 is a front perspective view of a control unit showing
our new design.

FIG. 2 is a rear perspective view of the control unit of FIG.
1.

FIG. 3 is a front view of the control unit of FIG. 1.

FIG. 4 is a rear view of the control unit of FIG. 1.

FIG. 5 is a left side view of the control unit of FIG. 1.

FIG. 6 is a right side view of the control unit of FIG. 1.

FIG. 7 is a top view of the control unit of FIG. 1; and,

FIG. 8 is a bottom view of the control unit of FIG. 1.

The broken lines shown in the drawings form no part of the
claimed design.

1 Claim, 7 Drawing Sheets
